RAILROAD TIE

Filed Feb. 5, 1929

*Inventor,
George C. Blalick,
by Walter P. Gager
Attorney.*

UNITED STATES PATENT OFFICE.

GEORGE C. HABICHT, OF SNYDER, NEW YORK.

RAILROAD TIE.

Application filed February 5, 1929. Serial No. 337,648.

This invention relates to improvements in railroad ties and more particularly to a reinforced concrete tie.

One of its objects is the provision of a tie of this character which has been designed to afford a more uniform distribution of the load on the ballast, to present a greater bearing surface, and to effectively withstand the stresses of the forces passing into it.

10 Another object of the invention is to provide a comparatively light and inexpensive concrete tie which is constructed to retain its position in the ballast in which it is embedded, and which will materially reduce the 15 maintenance costs of street railway and steam track lines.

In the accompanying drawings:—

Figure 1 is a top plan view of a tie embodying my invention. Figure 2 is a side view thereof. Figures 3, 4 and 5 are cross-sections on the correspondingly numbered lines in Figure 1. Figure 6 is a side view of a modified form of my invention. Figure 7 is a cross-section thereof on line 7—7, Figure 6. 25 Similar characters of reference indicate corresponding parts throughout the several views.

My improved tie is preferably constructed of reinforced concrete and in the embodiment thereof shown in Figures 1 to 5 inclusive, it comprises a central or span portion 10, end portions 11 and rail-engaging portions 12, the latter having bolts 13 embedded therein for anchoring the rails thereto. The span portion of the tie is substantially triangular in cross-section, being flat across its top face, as indicated at 14, and having its opposite sides or faces 15 converging downwardly. The top and bottom corners of this span portion are preferably chamfered or flattened, as indicated at 16 in Figure 5.

The end portions 11 of the tie are likewise substantially triangular in cross-section, being flat across their bottom faces 17 and having their opposite sides 18 converging upwardly, as shown in Figure 3. The top and bottom corners of these portions are also chamfered, as indicated at 19 in the same figure.

50 The rail-engaging portions 12 are rec-

tangular in cross-section and form between the span portion 10 and end portions 11 oppositely facing upright shoulders 20 and 21, respectively, which prevent shifting of the tie transversely of the tracks.

In the modified form of the invention shown in Figures 6 and 7 the tie 22 is of the same cross-section from end to end as is the span portion of the tie previously described.

By this construction, a comparatively light, 60 strong and durable tie is produced which not only absorbs the stress of the tie against the ballast, but affords an extensive bearing face therefor, eliminating the liability of the ties shifting in the ballast. Owing to the cross-sections of the span and end portions of the tie, the latter will retain its position in the ballast and be held against shifting both lengthwise and crosswise thereof, and it will not be disturbed by the forces passing over 70 the rails. Furthermore, the cross-section of such portions resists the compression and tension strains produced by the trains passing over the rails.

I claim as my invention:—

1. A railroad tie consisting of a span portion, rail-engaging portions and end portions, the span portion and end portions being of substantially triangular cross-section with their bases oppositely disposed.

2. A railroad tie consisting of a span portion, rail-engaging portions and end portions, the span portion having a flat top wall and downwardly-converging side walls, the end portions having flat bottom walls and upwardly-converging side walls, and the rail-engaging portions being rectangular in cross-section.

3. A railroad tie consisting of a span portion, rail-engaging portions and end portions, the span portion having a flat top wall and downwardly-converging side walls, the end portions having flat bottom walls and upwardly-converging side walls, and the rail-engaging portions being rectangular in cross-section and forming with the adjoining span and end portions oppositely-facing shoulders disposed transversely of the tie.

GEORGE C. HABICHT.
